CONCEALED ROOFING NAIL

Clarence Bugher, Kokomo, Ind.

Application October 17, 1934, Serial No. 748,587

1 Claim. (Cl. 108—33)

This invention relates to the art of roofing nails to be employed to secure roofing materials in the form of roll roofing or cut shingles of composition materials to a deck in such manner that the shank of the nail is at all times covered over where it passes through the roofing material itself so as to prevent leakage of water down around the shank. Heretofore considerable difficulty had been encountered in maintaining roofs against leakage where the heads of attaching nails are left exposed. Within a very short time such nails will generally work loose under the freezing and thawing action so that the nails will actually lift. Also simultaneously the roofing material will draw and tend to cause the hole through which the nail passes through the roofing material itself to increase in size so that water may readily pass down around the nail through the roofing material. This difficulty is not encountered where the nail head is covered over by a lap of the roofing material. However, it is apparent that the ordinary nail can not be driven down through the roofing and have its head concealed without leaving a lap unsecured thereover.

25 It is an important object of my invention to provide a nail structure which may be driven through roofing material in such a manner that the next row of material thereabove may be lapped over the nail proper, but at the same 30 time have that over-lapping edge secured in place by that same nail.

Further objects and advantages of my invention are found in the simplicity of the structure employed and in the simplicity of the operations thereof. The nail used is in one piece and may be readily formed automatically at relatively low cost.

The invention is described with reference being made to the accompanying drawing, in which

1934, Serial No. 748,587

Fig. 10. a bottom plan view.
Like characters of reference indicate like parts
throughout the several views in the drawing.

Referring first to the form of invention as shown in Figs. 2-4, I take a flat piece of metal and bend one end downwardly therefrom substantially at right angles thereto to form a shank 10 which is herein shown as being U-shaped in cross section. The lower end is pointed to facilitate driving. From the upper end of this shank 10 a head portion 11 extends for a distance therefrom to have turned upwardly from the other end an arm 12 to be left approximately at right angles thereto. The upper end of this arm 12 is provided with one or more over-turned barbs 13. The length of the arm 12 is made to be less than the head 11 and the lengths of the barbs 13 are made to be not more than the thickness of the roofing material to be employed and preferably less than such thickness.

Particular attention is directed to the fact that the shank 10 is formed by turning down an end of the metal from the head 11 and that this shank is formed to be under the head 11 by having the vertical edges of the shank turned around thereunder to leave a more or less reenforced juncture between the shank and the head 11. 25

In employing the nail just described, a lower row 14 of roofing material, whether it be strip shingles, individual shingles, or roll roofing, is put in position on the roof deck 15', then a row of the nails just described are driven in a line below the upper edge of that material in the row 14. These nails are driven by striking the head 11 directly over the shank 10 which will cause the shank 10 to pierce the material in the row 14 and travel on into the deck 15' thereunder. By reason of the column-like shank open within, the center of the shank will be filled with the material of the roof and deck and this filling resists greatly the withdrawal of the nail. When the nails are driven as above indicated, they will be in some such position as indicated in Fig. 1 where the arm 12 is extending normally from the roof as indicated by the dash lines.

Then the next row 15 of the roofing material is laid in position with its lower edge over-lapping the upper portion of the row 14. The lower edge of the row 15 is positioned by resting against the upturned arms 12. These arms 12 are then bent around and over the lower edge of the row 15 to come into the position as indicated by the solid lines wherein the barbs 13 penetrate the material and thus firmly grip the lower edge of that ma- 50 55

material between the arm 12 and the head 11 of each nail.

It is thus to be noted that the shank 10 of each nail is spaced upwardly a distance from the lower edge of the over-lapping row 15 so that this over-lapping edge thoroughly conceals and covers over the places in the row 14 where the nail shanks have passed through the roofing material. By reason of the close bending of the shank 10 into the column structure immediately adjacent the under side of the head 11, the juncture of that head with the shank is reenforced and prevented from being bent upwardly under wind pressures.

Referring to Figs. 3 and 4, particularly, the juncture between the head 11 and shank 10 is so formed that the center portion of the head 11 extends horizontally to the outer-most vertical line of the shank 10 as at *a* whereas the lateral edges of the head 11 terminate at the points *b*, or about the central vertical plan of the shank. By this formation there is not a straight line bend between the head 11 and shank 10, but an angular one which causes the resistance to bending between the two members at their juncture.

Of course the shank 10 may be formed by bringing its free vertical edges around to meet as in Figs. 5 and 6 to form a complete circular column where it is desired to do so. The same result may be accomplished by forming the nail from wire as indicated in Figs. 7 and 8 where the shank 16 is left in the round condition with its lower end pointed and then a portion of the wire is flattened to be bent around from the upper end of the shank to form the head 17, arm 18 and barbs 19. Preferably the juncture between the flat head 17 and round shank 16 is made by bending the flat portion away from the round first to the right and then around sharply to the left as in Figs. 7 and 8 so that there is an over-lapping of the shank 16 by the head 17 causing hammer blows in driving the shank to be delivered in the direction of the length of the shank to flatten the head against the end of the shank and seat the shank without bending it.

Of course, the nail may be formed as in Figs. 9 and 10 from flat material to have the shank 20 left in the flat condition. However, there may be some resistance wherein the flat shank 20 will not afford sufficient resistance to withdraw from the roof deck to afford the safety required. The forms above described afford more resistance to withdrawal than will the perfectly flat shank 20. The nails in any form may be provided to have shanks of lengths suitable for the job. For instance, where the roofing material is to be laid

directly over a wooden deck, the shank is of that length which will preferably terminate by its sharpened end just before it passes through the deck to the under side. Where the roofing material is to be laid over an old roof, the shank will be made longer so that it will pass through the old roof and well within the deck thereunder. Of course, the shanks may be made sufficiently long to penetrate entirely through the wooden deck although after the deck is once passed through, further extension of the shanks therefrom affords no particular advantage.

It is to be noted that the proportioning of the nail is preferably made to be such that the shank length is approximately equal to the length of the head, particularly where a new roof is being laid directly on the wooden deck. This proportion, however, will be changed where the shanks must be longer to pass through an old roof into the deck, in which case the head is preferably left the same length, but the shank is increased to be somewhat longer than the head, being in some cases twice that length.

In all of the forms shown, the sharpened point of the nail end is derived from the flat end of the arm 12 or 18, of the adjacent nail when in the flat form. That is, as the nails are formed in blank, the point is punched out to leave the barbs 13 or 19 which are afterwards bent around as above described.

While I have herein described my invention in the best forms as now known to me, it is entirely obvious that structural changes may be made without departing from the spirit of the invention and I, therefore, do not desire to be limited to those precise forms beyond the limitations as may be imposed by the following claim.

I claim:

A concealed roofing nail formed from a single sheet metal strip comprising an elongated non-perforate head, a shank with a longitudinal U-shape channel extending downwardly from one end of the head substantially at right angles thereto with the parallel edges of the channel toward and under the head, the walls of the channel next to the head being bent thereunder into contact therewith and the edges of the channel being inwardly of the edges of the head and connected with the edges of the head all to reenforce the joint and deliver stresses on the head longitudinally of the shank in driving the nail, and an arm bendable from the head at its opposite end adapted to be folded around the edge of the roofing material overlapping the head.

CLARENCE BUGHER. 55
